United States Patent Office

Des. 229,547

Patented Dec. 11, 1973

229,547

BOTTLE

Kenji Hanamura, Tokyo, Japan, assignor to Tancho
Co., Ltd., Higashi-ku, Osaka, Japan

Original design application Dec. 31, 1970, Ser. No.
26,716. Divided and this application Oct. 14, 1971,
Ser. No. 189,481

Term of patent 14 years

Int. Cl. D9—01

U.S. Cl. D9—157

FIG. 1

FIG. 2

FIG. 3

FIG. 4

FIG. 5

FIG. 6

FIG. 1 is a top plan view of a bottle showing my new design;

FIG. 2 is a side elevational view;

FIG. 3 is a bottom plan view thereof;

FIG. 4 is a top plan view of another embodiment of my new design;

FIG. 5 is a side elevational view; and

FIG. 6 is a bottom plan view thereof.

The bottle is symmetric, and the elevation view is the same from all directions.

This application is a division of application Ser. No. D. 26,716 filed Dec. 31, 1970 now Pat. No. D. 223,997 patented June 27, 1972.

I claim:

The ornamental design for a bottle, as shown and described.
